J. S. MEAD.
COLLAR BUTTON.
APPLICATION FILED FEB. 21, 1921.

1,425,670.

Patented Aug. 15, 1922.

INVENTOR:

James S. Mead.

BY *Allen Allen*
ATTORNEYS.

UNITED STATES PATENT OFFICE.

JAMES S. MEAD, OF CINCINNATI, OHIO.

COLLAR BUTTON.

1,425,670.

Specification of Letters Patent. Patented Aug. 15, 1922.

Application filed February 21, 1921. Serial No. 446,712.

To all whom it may concern:

Be it known that I, JAMES S. MEAD, a citizen of the United States, and a resident of the city of Cincinnati, in the county of Hamilton and State of Ohio, have invented certain new and useful Improvements in Collar Buttons, of which the following is a full, clear, and exact description, reference being had to the accompanying drawings, forming 10 part of this specification.

My invention relates to collar buttons or clasps, which are more particularly adapted for engagement with the neck band of a shirt and the rear buttonhole of detachable 15 collars, such as are common in men's wear at the present time.

There have been devices of the same general character as that of my invention in the past, i. e., strips of metal with tongues for 20 engaging within the neck band of a shirt, and another tongue extending out through the hole in the band, and through the hole in the rear of a collar.

It is the object of my invention to improve 25 upon such devices, making provision for greater security in the collar attachment, simpler manufacture and equal extent of engagement with the various parts, and better grasp throughout.

30 This object I accomplish by that certain construction and arrangement of parts to be hereinafter more specifically pointed out and claimed.

In the drawings,

35 Figure 1 is a perspective view of the device.

Figure 2 is a perspective view showing the device mounted in the neck band of a shirt.

Figure 3 is a sectional detail taken 40 through the shirt band and collar, as secured together by the button device.

Figure 4 is a side elevation of the button device.

45 Figure 5 is a view of the blank from which the device is made.

The button is formed (Figure 5) of a piece of metal stamped out with a body 1 with two tongues or tabs 2, 2, and a third tongue or tab 3 centrally of the body and 50 extending in the same direction as the end tabs 2.

This central tab has a small tongue cut in its body as at 4, the tongue being pressed outwardly from the tab, so that when the tab

is bent over as at 5, the tongue 4 will stand 55 upwardly.

It will be noted the tab 3 is bent so as to lie over the body of the piece, but spaced away therefrom, and that no bending or alteration in the tabs 2 is necessary. 60

When in use, the body portion is inserted behind the outer portion of the neck band 6, of a shirt 7, with the tongue 3 extending out through the button hole 8 in the shirt band.

The collar 9, when placed on the button, is 65 thrust over it, so that the body of the tongue extends downwardly through the button hole in the collar, and the small tongue 4 extends upwardly in the inside of the collar.

The strain, which tends to dislodge the 70 collar from the neck band of a shirt, is an upward pull on the collar in some cases and a downward pull on the collar in others.

The chief strain is the upward one, which is taken care of by the large tongue 3. The 75 downward strain or the upward pull, on the neck band of the shirt, is taken care of by the small tongue 4.

Due to the fact that the tabs 2, 2, extend 80 upwardly with relation to the downwardly extending tongue 3, there will be no metal showing beneath the neck band of the shirt, as might readily be the case with narrow neck bands, should the said tabs be turned downwardly, as has been the familiar practice 85 in devices of this nature.

My entire structure is very simply formed up by press work, with a minimum of operations and is entirely effective in holding stiff or soft collars to the neck bands of shirts. 90

Having thus described my invention, what I claim as new and desire to secure by Letters Patent, is:—

A collar button comprising a body portion, having tabs extending upwardly from 95 the ends thereof, another tab formed between the terminal tabs and bent downwardly from the upper edge of the body portion between the upward tabs, and a small tongue formed out and bent upwardly 100 from the said bent down tongue, said small tongue being located beyond the line of fold between the bent down tongue and the body portion, and in substantially the same vertical plane as the bent down tongue, as and for 105 the purpose described.

JAMES S. MEAD.
